(57) **CLAIM**

I claim the ornamental design for a "hydroponic plant cultivating apparatus," as shown and described.

DESCRIPTION

FIG. 1 is the front perspective view showing a hydroponic plant cultivating apparatus showing my new design.

FIG. 2 is a front elevation view of the hydroponic plant cultivating apparatus of FIG. 1.

FIG. 3 is a right side elevation view of the hydroponic plant cultivating apparatus of FIG. 1.

FIG. 4 is a back elevation view of the hydroponic plant cultivating apparatus of FIG. 1.

FIG. 5 is a left side elevation view of the hydroponic plant cultivating apparatus of FIG. 1.

FIG. 6 is a top view of the hydroponic plant cultivating apparatus of FIG. 1.

FIG. 7 is a bottom view of the hydroponic plant cultivating apparatus of FIG. 1; and,

FIG. 8 shows a front perspective view of another embodiment of a hydroponic plant cultivating apparatus of the Applicant's invention.

In the Figures, the dashed lines on the body of the hydroponic plant cultivating system are shown to define boundaries of various features that are not part of the claimed design. The area within the dashed lines are also not part of the claimed design. The dashed lines for the wheels beneath the hydroponic plant cultivating apparatus are shown for environmental purposes and form no part of the claimed design.

1 Claim, 7 Drawing Sheets
